UNITED STATES PATENT OFFICE.

GUSTAF I. JOHNSON, OF MALDEN, MASSACHUSETTS.

DESIGN FOR A FLASH LIGHT.

Application filed February 21, 1922. Serial No. 816. Term of patent 3½ years.

To all whom it may concern:

Be it known that I, GUSTAF I. JOHNSON, a citizen of the United States, residing at Malden, in the county of Middlesex and State of Massachusetts, have invented a new, original, and ornamental Design for a Flash Light, of which the following is a specification, reference being had to the accompanying drawing, forming part thereof.

Figure 1 is a plan of a flash light showing my improved design.

Figure 2 is a side elevation of the same.
Figure 3 is an end view of the same.

I claim:

The ornamental design for a flash light as shown.

GUSTAF I. JOHNSON.

Witnesses:

WALTER E. LOMBARD,
NATHAN C. LOMBARD.
